HINGE

Glenn W. Dettinger, Plainwell, Mich.

Application March 9, 1959, Serial No. 54,910

Term of patent 14 years

(Cl. D10—9)

Fig. 1 is a front elevation of a hinge, showing my new design.

Fig. 2 is a reduced top plan view of the hinge in closed position.

Fig. 3 is a front oblique view of the hinge in closed position.

Fig. 4 is a front oblique view of the hinge in partially open position.

The essential features of the design reside in the portions shown in solid lines.

I claim:

The ornamental design for a hinge, substantially as shown and described.
